UNITED STATES PATENT OFFICE.

BENJAMIN H. PURCELL, OF TERRE HAUTE, INDIANA, ASSIGNOR TO THE AUTOMATIC MACHINERY COMPANY, OF TERRE HAUTE, INDIANA, A CORPORATION, OF INDIANA.

LEER FEEDER.

Application filed February 9, 1920. Serial No. 357,488.

To all whom it may concern:

Be it known that I, BENJAMIN H. PURCELL, a citizen of the United States, residing at Terre Haute, in the county of Vigo and 5 State of Indiana, have invented a new and useful Leer Feeder, of which the following is a specification.

My invention relates specifically to mechanism by which freshly formed glass articles 10 may be automatically delivered into a leer, but it will be understood that the mechanism which will be described may be utilized for other purposes.

In apparatus of the type to which my 15 invention is applicable there is an endless carrier, upon which the articles are transported to a position in front of a transversely-operating pusher-bar, of such character that movement of the articles may 20 be arrested while movement of the carrier may continue beneath them, stop mechanism being provided to act in synchronism with the pusher-bar to arrest the articles before arrival in front of the pusher-bar preliminary 25 to and during movement of said pusher-bar, and the object of my invention is to provide an effective stop mechanism which will not crush or injure the articles and will not become choked so as to prevent 30 operation of the machine.

The accompanying drawings illustrate 35 my invention. Fig. 1 is a plan of a machine embodying my invention, the receiving end of a leer being shown in horizontal section; Fig. 2 an elevation of the machine, adjacent portions of the leer being shown in vertical section; Fig. 3 a plan of my improved stop and an adjacent portion of an endless carrier on a larger scale; Fig. 4 a section on 40 line 4—4 of Fig. 3; and Fig. 5 a section on line 5—5 of Fig. 3.

In the drawings 10 indicates a main frame formed to be projected laterally through suitable openings 11 in the side walls of the 45 leer 12 at its receiving end. Mounted in frame 10 is an endless carrier 13 having an upper surface upon which articles 14 (dotted lines Fig. 3) may rest and be carried and capable of slipping beneath the 50 articles when they are arrested. Carrier 13 is driven by a suitable motor 15.

Arranged alongside carrier 13 is a pusher-bar 16 capable of traversing the carrier and shoving articles therefrom and onto a de-

livery platform 17 which leads to a carrier 55 (not shown) in the leer. Bar 16 is supported by suitable guides 18 and is operated by suitable links 19, levers 20, bars 21 and 22, roller 23 and cam 24 driven by motor 15. A fence 25 is placed across carrier 13 at the 60 far end of bar 16 to prevent articles 14 from being carried beyond the bar 16. Thus far the apparatus is of a common type.

In order to interrupt the flow of articles to positions in front of the pusher-bar I 65 provide a yielding gate of peculiar form. This gate comprises a main body 30 provided with sides 31 and mounted to reciprocate in a guideway 32 transversely of the carrier 13, reciprocation, in synchronism with bar 70 16, being obtained by means of link 33, lever 34, link 35, spring 36, bar 37 and roller 38 projected into cam 24 and advance of roller 23.

Mounted so as to slide freely longitudinally in body 30 are several stop-fingers 40, preferably, though not necessarily, of gradually decreasing length and bevelled forward ends. The weight of fingers 40 offers a required amount of resistance to 80 their movement in body 30 and this movement in one direction relative to body 30 is limited by pins 41 which engage a retainer 42 carried by body 30, and in the opposite direction of movement is limited by a bar 85 43 carried by guide-way 32. The stop-mechanism just described is mounted at the rear, or receiving, end of pusher-bar 16 and opposite a fence 44 arranged alongside carrier 13. 90

The operation is as follows:

Articles 14 are brought by carrier 13 to positions opposite the pusher-bar 16 and at regular intervals the pusher-bar is operated to shove the accumulated articles laterally 95 from the carrier onto platform 17. Just before pusher-bar starts, body 30 is moved toward carrier 13 so as to project fingers 40 across the carrier in front of oncoming articles. If, by chance, an article should be 100 advanced to such a position relative to the first finger that said finger could neither arrest nor push it back, it is apparent that further forward movement of this finger will be arrested by the article, without injury to the article or the mechanism, and that the body 30 will continue in its projecting movement and that one or another of 105

fingers 40 will be driven into position to arrest the article before any part of it can come into position in front of the pusher-bar.

5 Upon return movement of body 30 any displaced fingers 40 will be successively picked up by retainer 42 and returned to initial position, bar 43 insuring against any improper overthrow of fingers 40 on such

10 return movement.

In case an article has progressed far enough in front of fingers 40 to reach a proper position in front of the pusher-bar before it starts forward it is apparent that 15 the bevelled ends of fingers 40 will tend to assist the article to reach this favorable position and thus prevent any possibility of crushing the article between fence 44 and the pusher-bar.

20 I claim as my invention:

1. The combination with an endless carrier, of a stop mechanism comprising a main body movable transversely of the carrier, a plurality of stop-fingers having 25 bevelled active ends associated with said body at successive positions lengthwise of the carrier and independently yieldingly movable by said body transversely of the carrier.

30 2. The combination with an endless carrier, of a stop mechanism comprising a main body movable transversely of the carrier, a plurality of stop-fingers associated with said body at successive positions lengthwise 35 of the carrier and independently yieldingly movable by said body transversely of the carrier.

3. The combination with an endless car-

rier, of a stop mechanism comprising a main body movable transversely of the carrier, a 40 plurality of stop-fingers having bevelled active ends frictionally carried by said main body at successive positions lengthwise of the carrier and yieldable on the main body longitudinally, and one-way engaging means 45 carried by said fingers and main body.

4. The combination with an endless carrier, of a stop mechanism comprising a main body movable transversely of the carrier, a 50 plurality of stop-fingers frictionally carried by said main body at successive positions lengthwise of the carrier and yieldable on the main body longitudinally, and one-way engaging means carried by said fingers and main body.

5. The combination with an endless carrier, of a stop mechanism comprising a main body movable transversely of the carrier, a 55 plurality of stop-fingers having bevelled active ends frictionally carried by said main body at successive positions lengthwise of the carrier and yieldable on the main body longitudinally.

6. The combination with an endless carrier, of a stop mechanism comprising a main 65 body movable transversely of the carrier, a plurality of stop-fingers frictionally carried by said main body at successive positions lengthwise of the carrier and yieldable on the main body longitudinally.

In witness whereof, I have hereunto set my hand at Terre Haute, Indiana, this 24th day of January, A. D., one thousand nine hundred and twenty.

BENJAMIN H. PURCELL.
